UNITED STATES PATENT OFFICE.

BRUNO VERSEN, OF DORTMUND, GERMANY.

ROUNDABOUT ROLLING-MILL

1,044,953.

Specification of Letters Patent.

Patented Nov. 19, 1912.

Application filed August 16, 1910. Serial No. 577,448.

To all whom it may concern:

Be it known that I, BRUNO VERSEN, a subject of the German Emperor, and resident of Dortmund, Germany, have invented certain new and useful Improvements in Roundabout Rolling-Mills, of which the following is a specification.

The invention relates generally to a continuous rolling mill and particularly a rolling mill in which the rolling trains are arranged concentrically around a common axis with the rollers of the respective trains arranged at an angle of 90° to each other.

The main object of the present invention is to utilize the annular arrangement of the rollers with respect to each other to allow the bar being rolled to be properly handled by the successive rolls without the necessity of the usual turning of the bar in the passage from one set of rolls to the next.

The invention in its preferred details of construction will be described in the following specification, reference being had particularly to the accompanying drawings 25 in which—

Figure 1 is a vertical section of a rolling mill constructed in accordance with my invention. Fig. 1^a is a view similar to Fig. 1, but illustrating a motor on the central shaft. Fig. 2 is a plan of a mill in accordance with that type shown at the right of Fig. 1. Fig. 3 is a diagrammatic view showing the connection of a series of mills for a particular type of plant. Fig. 4 is a diagrammatic plan of a guide from one mill to another as illustrated in Fig. 3. Fig. 5 is an enlarged sectional view of the guide between the respective sets of rolls of the mill. Fig. 6 is a detail view of the means 40 for controlling the pressure between said gear and the driving pulley.

In detailed structure, and with particular reference to that construction shown at the left side of Fig. 1, the improved mill, 45 comprising a foundation frame (a) on which the respective trains are made up, as pairs of coöoperating rolls (b). The respective pairs of rolls are concentrically arranged with relation to a central axis, as will be clearly noted from Fig. 2 of the drawings, and each coöperating pair of rolls 50 are arranged at an angle of 45° to the plane of the bed (a).

The motive power for the mill is furnished through an approximately driven central shaft (f), supported at its lower end

in a suitable bearing and at intermediate points by conical frame structures (d), which are directly and indirectly supported from the bed (a). The frame structures (d) are for the purpose of the present invention similarly constructed including bearing sleeves (1) and conical canopies (2) projecting therefrom. The lower pair of supporting frames open upwardly while the upper pair open downwardly. A rigid frame structure is thus provided as will be obvious. Secured upon the shaft (f) between the upper pair of frame structures is a gear (c), a similar gear being arranged 70 between the frame structures of the lower pair. The respective rolls (b) carrying shafts (3) which project from the rolls are supported in suitable bearings projecting from the frame structures (d), and are terminally provided with gears (e) meshing with respective gears (c), the shafts of adjacent rolls being projected in opposite directions, that is one pair will project downwardly and inwardly being operated by the 75 lowermost gear (c) while the shafts of the next pair of rolls project upwardly and inwardly and are operated by the upper gear (c). By this construction the alternate rolls are driven from opposite points, so that as 80 will be plain from Fig. 1 of the drawings, the respective adjacent rolls are set at an angle of 90° to each other. The gears (e) of the respective sets of rolls in the direction of travel of the material being operated 85 upon bear such ratio to the driving gear and to each other that the rotation of each successive pair of rolls is increased, as is usually necessary in mills of this type to take care of the increased length of material. 90

In the type of mill where the rolls are to be driven at comparatively high speed as in handling small material, the rolls arranged exactly as previously described may be frictionally driven in order to diminish the noise 100 as much as possible. Under these circumstances, reference being had to the right hand side of Fig. 1, the gears (c) are replaced by frictional wheels (k), and the driving gears (e) replaced by friction rollers (e'). The friction rollers (e') are journaled in stirrup shaped frames (k') secured to brackets (l), supported from the respective frames (d). Levers (m) project from these frames, respective levers of each pair 110 of rolls being spring pressed in the outward direction, or in that direction necessary to se-

cure the desired frictional contact, by means of springs (n). Levers (m) which are fulcrumed at (o) on the supports from the frames (d) permit a yielding necessary to the proper frictional drive of the parts in the possible imperfection of such parts as will be understood.

In the travel of the bar from one roll to the next it is guided through the medium of a channel shaped guide member (p). This guide member is arranged between each pair of rolls and includes a supporting plate (4) secured to one of the frames (d) preferably the lower one of the upper pair and a guide plate (5) arranged at an angle to the plate (4). At suitable intervals throughout the lengths of the channels (p) are arranged guide rollers (q). These guide rollers are formed with channels or peripheral 20 grooves (6) having a contour corresponding with the cross section of the bar being rolled. Under ordinary circumstances the guide rollers may be rotated by the travel of the bar thereagainst, but in special circumstances as where the sectional area of the bar being rolled is simple, or the guides long, said guide rollers may be independently and positively driven through the medium of pulleys (r) fixed upon shafts (7) carrying 25 said guide rollers which pulleys may be driven from any suitable power by cables (8), all as particularly seen in Fig. 5.

The mill may be operated directly from an electric motor where high speeds are desired, as shown at (9) in Fig. 1, or the shaft (f) may be driven through the medium of gears (h) and (i) through a shaft (g), as shown at the left hand side of Fig. 1.

In operating this type of mill the travel 40 of the bar is, as will be understood, from one set of rolls to the next throughout the series of trains provided in the respective mill, the bar being automatically guided in its travel from one set of rollers to the next by means 45 of the guide and rollers therefor, as previously described. In this operation the handling of the bar is in effect automatic as by the opposite disposition of adjacent rolls the fin produced on the bar by one set of 50 rolls is eliminated by the next set of rolls without the necessity of turning the bar. It will be thus understood that the bar to be rolled after leaving one groove or matrix is guided circularly along these guide rollers 55 without any sudden change of direction, the centrifugal force pressing it into the groove of the guide rollers whereby it is conveyed surely and without any rotation from one mill to the next. During this passage any 60 shortening which may happen to occur does not encounter any obstacle, as the chord being shorter than the arc permits such shortening without interference, as will be readily obvious.

65 The improved type of mill readily lends

itself for carrying out a determined rolling program, in that the several continuous rolling mills may be readily combined in different arrangements. As noted diagrammatically in Fig. 3, I have shown the combination of four such rolling mills arranging these mills to show 18 rolling operations. In this particular combination mill I is driven directly by the motor (M) while mills II and III are driven through the medium of the transmission gears (S) and (S'). Mill IV is driven in any suitable manner and is used as a finishing mill. The mills are connected by guide channels similar in all respects to the guide channels (p) previously described, so that the material is directed from one mill to the next succeeding mill as shown by the parallel lines in said Fig. 3. In this connection it is to be understood that the conveying channels or guides from one mill to the other are arranged tangentially to the respective rolling trains of the connected mills, having between such points of connection a gradual curve corresponding to the curvature imparted to the bar in its 90 travel through the final mill.

In Fig. 3, is shown diagrammatically two complete mill sets, in each of which mill I is taken as the mill at which the rolling starts. One mill set includes mills I-II^a— and 95 III^a, while the other set includes mills I-II—III—IV. All description of the above detailed construction of the mill applies to each mill in each set. The first set is adapted for rolling irons of middle or 100 small strength, while the second is used for larger profiles of material.

Having now fully described my said invention, what I claim and desire to secure by Letters Patent, is:

1. In a rolling mill of the kind described the combination with a framework of a vertical central shaft, means for driving the said shaft, a plurality of rolling frames radially and annularly arranged around said central shaft, and means for driving said rolling frames from said central shaft, substantially as and for the purpose set forth.

2. In a rolling mill of the kind described the combination with a framework of a central shaft, a driving motor provided on said shaft, a plurality of rolling frames radially and annularly arranged around said central shaft, and means for driving said rolling frames from said central shaft, substantially 115 as and for the purpose set forth.

3. In a rolling mill of the kind described the combination with a framework of a central shaft, a plurality of rolling frames radially and annularly arranged around said central shaft and means for driving said rolling frames from said central shaft, substantially 125 as and for the purpose set forth.

4. In a rolling mill of the class described, the combination with a frame-work of a 130

central shaft, a plurality of rolling trains arranged annularly around said central shaft on a part of a circle, the rolls of neighboring trains being arranged at an angle of 5 90 degrees with reference to each other, inclined driving gears secured to said central shaft, connections between said driving gears and the rolling trains and means for operating said central shaft.

10 5. In a rolling mill of the kind described, the combination with a frame-work, of a central shaft, a plurality of rolling trains arranged annularly around said shaft on a part of a circle, the rolls of neighboring 15 trains being arranged at an angle of 90 degrees with reference to each other, inclined driving gears secured to said central shaft, a means connecting said rolling trains with said driving gears, means for controlling the 20 pressure between said latter means and driving gears and means for operating the central shaft.

6. In a rolling mill of the kind described the combination with a framework of a central shaft, a plurality of rolling trains concentrically arranged around said shaft at suitable intervals from each other and on a part of a circle, means for driving said 25 rolling trains, circularly bent channel shaped 30 guides between the passes of the various rolling trains and guide rollers provided with a suitable groove and projecting into the said guide channels, substantially as and for the purpose set forth.

35 7. In a rolling mill of the kind described the combination with a framework of a central shaft, a plurality of rolling trains arranged on a part of a concentric circle around said shaft and at suitable intervals 40 from each other, means for driving said rolling trains, guide channels bent to an arc of

a circle and interposed between the passes of every two neighboring rolling trains and a plurality of suitably grooved guide pulleys in the said guide channel and means for 45 driving said pulleys, substantially as and for the purpose set forth.

8. In a rolling plant the combination of a plurality of rolling mills comprising each a central shaft, a plurality of rolling trains 50 arranged around the said shaft on a part of a circle which is concentric to the shaft, means for driving said trains from the central shaft, means for individually driving the shaft of each rolling mill, curved guide channels provided between the passes of the rolling trains of each rolling mill and a curved 55 guide channel between the pass of the last rolling train, of one mill and the pass of the first rolling train of the next mill, substantially as and for the purpose set forth.

9. In a rolling plant the combination of a plurality of rolling mills comprising each a central shaft, a plurality of rolling trains arranged around said shaft on a part of a circle which is concentric to the shaft, means for driving said rolling trains from the central shaft, means for driving by groups the 60 shafts of said rolling mills, curved guide 65 channels provided between the passes of the rolling trains of each rolling mill and a curved guide channel between the pass of the last rolling train of one mill and the pass of the first rolling train of the following mill, substantially as and for the purpose 70 set forth.

In testimony whereof I have hereunto set my hand in presence of two witnesses.
